UNITED STATES PATENT OFFICE.

CHARLES LEFKOWITZ, OF NEWARK, NEW JERSEY.

CARBOY BONNET.

Application filed October 10, 1923. Serial No. 667,719.

To all whom it may concern:

Be it known that I, CHARLES LEFKOWITZ, a citizen of the United States, residing in the city of Newark, in the county of Essex and State of New Jersey, have invented a new and Improved Carboy Bonnet, of which the following is a full, clear, and exact description.

My invention has for its object to provide 10 a carboy bonnet which serves to protect the projecting neck of a bottle disposed in the carboy, the bonnet having two parallel strips secured to sides of the bonnet respectively by means of which the bonnet may be readily 15 fastened to a carboy.

Another object of the invention is to construct the bonnet with sides converging upwardly which are connected at their upper portions by a horizontal member, this construction 20 making the bonnet strong and durable.

Still another object of the invention is to provide a bonnet with a resilient member which will press against the cork and serve 25 to hold the cork in the bottle.

Additional objects of the invention will appear in the following specification in which the preferred form of my invention is described.

30 In the drawings similar reference characters refer to similar parts in both views in which,

Fig. 1 is a perspective view showing the upper portion of a carboy to which is secured my carboy bonnet; and

35 Fig. 2 is an enlarged transverse section of Fig. 1.

On referring to the drawings it will be seen that the carboy 5 has a top 6 to which 40 the carboy bonnet 7 is secured. This carboy bonnet is constructed with four sides 8 which connect with each other at their edges, the said sides 8 converging upwardly and being connected at their top by a horizontal member 9, this horizontal member 9 being secured to the sides 8.

The bonnet has two parallel strips or members 10 spaced apart and secured to sides 8 of the bonnet, these strips or mem-

bers 10 having orifices 11 through which 50 screws 12 may be disposed to screw the bonnet 7 to the top 6 of the carboy. It will be understood by removing the screws 12 the bonnet may be raised from the top 6 of the carboy without damage to the neck 13 of 55 the bottle 14. However, when the bonnet is in place and is held in position by the screws 12, it will serve to protect the neck 13 of the bottle 14.

On referring to Figure 2 of the drawings 60 it will be seen that within the bonnet and secured to the inner sides 8, there are two bearing members 15 each having a bearing 16 in which the ends 17 of a leaf spring 18 are disposed. This leaf spring 18 is situated in a position to engage the cork 19 65 disposed in the neck of the bottle so that when the bonnet 7 is in position, the leaf spring 18 will hold in place the said cork 19.

Having thus described my invention what 70 I claim as new and desire to protect by Letters Patent is:

1. In a bonnet for carboys, a hollow body having four upwardly converging sides, each side being disposed at angles to adjacent sides, a top secured to the upper portions of the sides, and two parallel strips secured to opposite sides of the hollow body, respectively, by means of which the bonnet 75 may be secured to a carboy.

2. In a bonnet for carboys, a hollow body, and a leaf spring carried by the body for engaging at its central portion a cork for pressing the cork into a bottle when disposed in the carboy.

3. In a bonnet for carboys, a body having two bearings spaced apart and a leaf spring having its ends disposed in the bearings, the leaf spring being in position for pressing a cork into a bottle disposed in the carboy.

4. In a bonnet for carboys, a hollow body having four sides converging upwardly, a top connecting the sides, two bearings spaced apart in the hollow body and a leaf spring having its ends disposed in the bearings the leaf spring being in position for pressing a cork into a bottle disposed in the carboy.

CHARLES LEFKOWITZ.
